JOHN T. S. BROWN, JR., OF PROSPECT, KENTUCKY.

PIPE-CLAMP.

1,179,500.

Specification of Letters Patent. Patented Apr. 18, 1916.

Application filed December 1, 1915. Serial No. 64,543.

To all whom it may concern:

Be it known that I, JOHN THOMPSON STREET BROWN, Jr., a citizen of the United States, residing at Prospect, in the county 5 of Jefferson and State of Kentucky, have invented new and useful Improvements in Pipe-Clamps, set forth and described in the annexed specification.

This invention relates to pipe clamps of 10 the class designed to support a pipe when withdrawing it from, or lowering it in a deep well.

In withdrawing a drop pipe from a well the customary method is to connect suitable 15 tractive means with the pipe, and a stop, or clamp, comprising a pair of timbers provided with opposed concavities for the reception of the pipe, is disposed about the pipe, and secured thereon, next to the 20 ground, by means of transverse bolts. When the tractive means has reached the limit of its movement, the stop which is then removed from the ground, is released by loosening the bolts, and lowered to the 25 ground, and again secured. The tractive means is then eased off, the stop sustaining the pipe while a new hold is secured with the tractive means. In lowering the pipe in the well, the stop is initially secured on the 30 pipe a distance from the ground equal to the lowering movement of the tractive means and serves when it comes in contact with the ground to hold the pipe while the tractive means is being moved up to secure a 35 fresh hold. It also serves to catch and hold the pipe in case of any mishap to the tractive means. This having to shift the stop at every step in the progress of the withdrawal or lowering the drop pipe makes the 40 proposition a laborious and tedious operation.

An object of this invention is to provide means which while permitting a free withdrawal of the pipe will instantly check any 45 retrograde movement thereof.

Another object is the provision of means which will not oppose the lowering of the pipe as long as the movement thereof is steady, but will stop its descent if there is 50 a sudden acceleration of its movement, such as would occur if the tractive means should fail or its connection with the pipe slip.

A further object is the provision of means of the class described which may be conveniently manipulated, permitting expeditious 55

movement of the drop pipe, which will be efficient and durable in service and economical in construction.

With the foregoing and other objects in view, the invention consists of the novel 60 construction and arrangement of parts illustrated in the accompanying drawing, which forms a part of this specification, wherein is set forth an embodiment of the invention, but it is to be understood that such changes 65 and modifications may be resorted to as come within the scope of the appended claims.

Referring to the drawing wherein similar reference characters designate like parts in the several views Figure 1 is a perspective 70 view of my improved clamp showing it in connection with a pipe being lowered: Fig. 2, a detached detail of the centering device: Fig. 3, a detached view of one of the dogs.

Referring in detail to the drawing the 75 reference numeral —1— designates a base, or platform, which may be of any suitable material, comprising two sections united by transverse bolts —2— and having a central opening —3— of sufficient size to permit 80 the passage of a pipe of maximum size. Mounted on the base, about the opening are a plurality of guides or centering members —4— which are adapted to contact with a pipe —5— which depends through the 85 opening. Each of the guides comprises a tube —6— which is adjustably secured in bearings, or brackets —7— by suitable means such as set screws —8—, in order that it may be adjusted to and from the center 90 of the opening to accommodate pipe of different sizes. A rod —9— provided at each end with a longitudinal slot as —10 and 11—, is slidably disposed in the tube 6 and extends therefrom at each end. A wheel 95 —12— is rotatably mounted in the forward slot 10. A pin —13— passed transversely through the tube 6, near the rear end thereof, passes through the slot 11, and serves to prevent rotation of the rod, thus maintaining the wheel 12 in a vertical position. A coiled compression spring —14— disposed about the forward portion of the rod, bears 100 respectively against the forward end of the tube and a washer —15— which is secured on the rod in the rear of the wheel. The rear end of the rod is screw threaded for the reception of a nut —16— which holds the rod against the force of the spring.

The office of the spring is to yield and per- 110

mit joints in the pipe to pass. A plurality of dogs, or jaws —17—, are disposed about the opening 3 in position to be engaged with the depending pipe 5. The dogs are mounted on the platform in such a manner that they may be adjusted to seize different size pipe. Any suitable method of mounting may be used. As illustrated a channel shaped bracket —18— is employed, having 10 a plurality of alined transverse openings —19— in its opposed walls, which permit of the adjustment of the dog by means of a pin —20—. The dogs are substantially ovate in shape, and are provided with a 15 perforation —21— near the rear end for the passage of the pin 29, the forward end being provided with serrations —22— for engagement with the pipe. And an angular heel —23— at the rear end serves to 20 limit its upward movement. The dogs are reversible, thereby prolonging their usefulness.

As described the device will serve to control the pipe during withdrawal thereof, the dogs being adjusted so that their forward ends lie against the pipe at an inclination slightly above the horizontal so that they will yield freely to upward movement thereof but instantly bite into and 30 bring it to a stand still upon its slightest downward movement. When a pipe is being lowered the dogs must be held up out of contact with the pipe during the lowering movement. For this purpose use is made 35 of the apparatus now to be described. To the forward ends of the dogs, flexible connectives —25— are connected by suitable means such as clips —26. The connectives are connected to a common member such 40 as a ring, or hoop —27—, affording means whereby all the dogs may be lifted at one time. A plurality of ropes —28, 29— are connected to the hoop at equi-distant points, in such a manner as to lift evenly 45 thereon, and are led up over pulleys —30— which are removably attached to the pipe at a suitable height above the hoop. From the pulleys 30 the ropes lead downward to and through pulleys —31—, secured to the 50 platform. Traction exerted on the ropes after they have passed through the pulleys 31 will raise the hoop 27 and connected dogs and they will be maintained in the elevated position as long as the traction is 55 constant. This traction may be accomplished manually or as illustrated, by means of a weight —32— attached to the ropes after they have passed over pulleys —33—. Any relaxation of the tractive force on the 60 hoop will permit the dogs to drop and engage the pipe. The descent of the pipe and attached pulleys 30, would cause a slack in the ropes, which would allow the ring to fall, but that the slack is taken up by 65 the tractive force of the weight 32, as

long as the downward movement of the pipe is constant, but any sudden acceleration of its movement, such as would occur if the lowering cable —34— were to break, would cause a slackage which would permit 70 the dogs to drop before the weight 32 could accelerate to take up the slack so caused.

Practice has demonstrated that with the strongest pull possible exerted manually on 75 the ropes 28, 29, the dogs will engage instantly, with and hold the pipe on the severance, or easing off, of the cable 34.

It is thought that the construction, operation and advantages of this device will be 80 fully apparent to and appreciated by those conversant with the art to which it pertains, without more extended description.

Having thus described my invention so 85 that anyone skilled in the art pertaining thereto may make and use the same, I claim:

1. In a device of the character described, in combination, a platform having an opening for the passage of a pipe to be lowered, a clutch mounted on said platform and 90 adapted to be engaged with the pipe to prevent downward movement thereof, and means connected respectively with said clutch and pipe for preventing engagement of the clutch with the pipe during uniform 95 downward movement thereof, but permitting engagement upon sudden acceleration of said downward movement.

2. In a device of the character described, in combination with a platform having an 100 opening for the passage of a pipe to be lowered, dogs mounted thereon and adapted to be engaged with the pipe to prevent downward movement thereof, means for holding the dogs out of engagement with the pipe 105 during constant downward movement thereof but permitting said engagement upon any sudden acceleration of said downward movement.

3. In combination with a platform, having 110 an opening, a pipe to be lowered depending through said opening, a dog mounted on said platform and adapted to be engaged with said pipe to prevent downward movement thereof, a pulley removably attached to the pipe at a point elevated above the platform, a second pulley attached to the platform, a cord connected to said dog and leading up over said first named pulley thence downward under said second named 115 pulley and tractive means connected to said cord.

4. In combination with a platform having 125 an opening, a pipe to be lowered depending through said opening, a dog mounted on said platform and adapted to be engaged with said pipe to prevent downward movement thereof, a pulley removably attached to the pipe at a point elevated above the platform, a second pulley attached to the 130

platform, a third pulley supported at a point above said second named pulley, a cord connected to said dog and leading upward over said first named pulley thence downward under said second named pulley, thence upward over said third named pulley and a weight attached to said cord.

5. In combination with a platform having an opening, a pipe to be lowered depending through said opening, a plurality of dogs mounted on said platform and adapted to be engaged with said pipe to prevent downward movement thereof, a common member to which said dogs are connected and whereby they may be lifted in unison, pulleys removably attached to the pipe at a point elevated above the platform, other pulleys attached to the platform, cords connected to said common member and leading successively over said pulleys in the

order named, and tractive means connected to the rope.

6. In combination with a platform having an opening, a pipe to be lowered depending through said opening, a plurality of centering members disposed about said opening, said members adapted to yield to permit the passage of couplings in the pipe, a plurality of dogs mounted on said platform and adapted to be engaged with said pipe to prevent downward movement thereof, a pulley removably attached to the pipe at a point elevated above the platform, a second pulley attached to the platform, a cord connected to said dog and leading up over said first named pulley, thence downward under said second named pulley and tractive means connected to said cord.
